UNITED STATES PATENT OFFICE

HAROLD LOUIS MATTHES, OF MONROE, MICHIGAN, ASSIGNOR TO THE WEIS MANUFACTURING COMPANY, OF MONROE, MICHIGAN, A CORPORATION OF MICHIGAN

VISIBLE INDEX SYSTEM

Application filed January 26, 1928. Serial No. 249,525.

This invention relates to sliding trays or drawers, adapted to slide into and out of a cabinet, and more particularly to those which are so proportioned and arranged that they are especially adapted for use in connection with what is commonly called a visible index system, in which latter the sliding trays or drawers, arranged one above another, are provided with overlapping index cards which are easily accessible for inspection by merely pulling the tray or drawer outward, and then allowing it to hang downward to facilitate inspection of the cards or similar means held therein.

Generally stated, the object of the invention is to provide a novel and improved construction for permitting the tray or drawer to pull out and then hang downward in position to permit easy inspection of the cards or other things therein, involving a follower for the rear end of the tray or drawer, to which the rear end of the tray or drawer is detachably connected, having means for permitting the easy removal of the follower from the cabinet, if such is desirable or necessary.

It is also an object to provide certain details and features of improvement and combinations tending to increase the general efficiency and the desirability of a tray or drawer and follower construction of this particular character.

In certain respects, therefore, the construction herein shown and described is in the nature of an improvement on that shown and described in prior application No. 58,993, filed September 12, 1925, for a visible index system which application resulted in Patent No. 1,765,568.

To the foregoing and other useful ends, the invention consists in the matters herein-after set forth and claimed, and shown in the accompanying drawings, in which,—

Fig. 1 is a plan view of a cabinet tray or drawer having a follower embodying the principles of the invention, showing the cabinet in horizontal section, showing one tray and its follower in storage position in the cabinet, and showing the tray and follower below withdrawn to a position to permit

inspection of the things in the tray, being a section on line 1—1 of Fig. 2.

Fig. 2 is a vertical section on line 2—2 in Fig. 1.

Fig. 3 is an enlarged plan view of one of the trays, showing the follower therefor, portions of the tray being broken away for convenience of illustration, this view being on a larger scale than said previous views.

Fig. 4 is a transverse vertical section on line 4—4 in Fig. 3.

Fig. 5 is a detail section on line 5—5 in Fig. 3.

Fig. 6 is a similar view showing the tray in a different position.

As thus illustrated, the cabinet 1 may be of any suitable form or construction, being provided with horizontal walls or partitions 2 to form compartments therein for the trays and followers. Each compartment is provided with horizontal lateral guides 3, as shown.

Each tray 4 is of any suitable form or character, being preferably provided at its front end with a pull knob or handle 5, and at its rear end with the sheet-metal hooks 6, as shown. The tray or drawer thus formed may be supplied with overlapping visible index cards, as is common in cabinets of this kind, or the tray or drawer may be adapted to contain other things. Obviously, however, the tray or drawer must contain things which are held in place, as the tray is adapted to be pulled out and swung down into a vertical position, as shown in Fig. 6 of the drawings.

The follower to which the rear end of the tray is connected comprises a sheet-metal body 7 adapted to slide on the horizontal partition 2 behind the tray, and provided with loops 8 for detachably engaging the hooks 6 previously mentioned. The loops 8 have their end portions journaled in bearings 9 on the ends of the hinge members 10, which are hinge-connected to the plates 11, and provided with springs 12 on the pintles of said hinges thus provided, the portions 11 being rigid with the metal body portion 7 of the follower. Normally the hinges thus provided are in the position shown in Fig. 5 of the drawings; but when the tray is withdrawn

and allowed to hang down, these hinges then assume the position shown in Fig. 6 of the drawings. This permits of lost motion, so to speak, between the tray and its follower, because of the capacity for forward movement of the loops 8, thus increasing the space or distance between the tray and its follower under certain conditions. For this purpose, therefore, the follower is provided with stop rods 13 for engagement with the stationary stops 14 when the drawer is pulled out as far as possible and then allowed to hang down. These stop rods are mounted in outer bearings formed by the side portions of the follower body and in bearings 15 provided on the flat top of the follower. The inner end portions 16 of the two rods are bent around parallel with each other, as shown, and arranged to slide toward and away from each other under a guide 17 provided on the follower. A coiled spring 18 is provided under the guide 17, between the two parallel end portions 16 of the two rods, and this spring tends to keep the outer end portions of the rod 13 in the position shown, so that these end portions will engage the stops 14 when the tray or drawer is pulled out. However, should it become desirable to remove the follower from the cabinet, the two end portions 16 of the rods can be moved toward each other, using these two end portions as handles to be engaged by the thumb and fingers, and in this way the end portions of the rods will be disengaged from the stops 14 and the follower can be removed from the cabinet. Of course, the tray hooks 6 can be easily unhooked or disengaged from the loops 8, without the necessity of removing the follower from the cabinet, but the follower can then also be removed if such is desirable or necessary.

When the tray and its follower are pushed back into the cabinet, the hinge springs 12 will then operate to space the follower and the tray the normal distance apart, as they are in Fig. 5. But with the invention thus shown and described the tray or drawer is easily pulled out, and the hinges by which the loops 8 are connected to the follower body 7 then serve as lost-motion connections to permit movement of the tray after the follower has stopped, so that the tray or drawer can then hang down to facilitate the inspection of things carried or held therein.

What I claim as my invention is:

55 1. In a visible index system, the combination of a cabinet, a tray slidable therein, a follower for the inner end of the tray, removable as hereinafter stated from the cabinet, the cabinet having means to provide guides 60 for said tray and follower, and to keep the tray and follower in the same plane, means to limit the outward movement of the follower, a lost motion connection between the follower and the tray having means permitting movement of the tray away from the follower,

after the follower reaches the limit of its outward movement, means whereby the tray may swing down and hang vertically, together with manually operable means on the follower for rendering inoperative said means to limit the outward movement of the follower to permit disconnection and removal of the follower from said cabinet.

2. A structure as specified in claim 1, said means to limit the outward movement of the follower comprising movable stops on the follower, and stationary stops on the cabinet, said stops all in a horizontal plane, and said manually operable means being adapted to move the movable stops horizontally toward each other to disengage them from said stationary stops.

3. A structure as specified in claim 1, said means to limit the outward movement of the follower comprising movable stops on the follower and stationary stops on the cabinet, and said manually operable means being adapted to move the movable stops toward each other to disengage them from said stationary stops, together with a spring acting on said movable stops to yieldingly keep them in operative position.

4. A structure as specified in claim 1, said means to limit the outward movement of the follower comprising movable stops on the follower and stationary stops on the cabinet, and said manually operable means being adapted to move the movable stops toward each other to disengage them from said stationary stops, and said manually operable movable stops and means for operating them comprising rods having their outer ends disposed in position to engage the stationary stops and having their inner end portions bent parallel into longitudinal position to form handles constituting the operating means therefor, together with a compression spring between said parallel portions to keep the movable stops normally pressed outward in operative position.

5. In a visible index system, the combination of a cabinet, a tray slidable therein, a follower for the inner end of the tray, the cabinet having means in a horizontal plane to provide guides for said tray and follower, and to keep the tray and follower in the same plane, means to limit the outward movement of the follower, a lost motion connection between the follower and the tray permitting movement of the tray away from the follower, after the follower reaches the limit of its outward movement, means whereby the tray may swing down and hang vertically, said lost motion connection comprising spring controlled hinges on the follower, and means connecting said hinges to the inner end of the tray.

6. A structure as specified in claim 5, said spring hinges having loops forming the said connecting means therefor to the tray, with

hooks in the tray to detachably engage said loops, whereby the tray can be unhooked from said loops when the tray is withdrawn from the cabinet.

5 7. A structure as specified in claim 5, said spring hinges each comprising a member pivoted on a horizontal axis to which the tray is connected, operative about a horizontal axis, the spring of each hinge acting to normally 10 keep said movable member thereof in raised position but permitting such member to yieldingly swing downward when the tray is withdrawn and allowed to swing downward.

15 Specification signed this 23rd day of January, 1928.

HAROLD LOUIS MATTHES.
